UNITED STATES PATENT OFFICE

JOHN T. FITZSIMMONS, OF ANDERSON, INDIANA, ASSIGNOR TO DELCO-REMY CORPORATION, OF DAYTON, OHIO, A CORPORATION OF DELAWARE

IGNITION TIMER

Application filed November 21, 1927. Serial No. 234,610.

This invention relates to ignition apparatus for internal combustion engines and particularly to the control of the ignition timer by a centrifugal device responsive to the speed 5 of the engine for advancing the timing of the spark.

One object of the present invention is to provide for certain improvements in a governor of the flat weight type for an ignition 10 timer cam. In this type of governor the ignition timer cam is rotatably supported by the ignition timer shaft and is rotatable relative thereto. The cam is connected with the shaft through the ignition governor which 15 comprises a weight supporting plate driven by the shaft and carrying pivoted weights each cooperating with a lever mechanically connected with the cam. More specifically it is an object of the present invention to provide 20 means for retaining the weights upon the weight supporting plate while permitting the weights to move freely outwardly in response to the increase of centrifugal force or inwardly due to the action of springs which 25 restore the weights to normal position.

Further objects and advantages of the present invention will be apparent from the following description, reference being had to the accompanying drawings, wherein a preferred form of embodiment of the present 30 invention is clearly shown.

In the drawings:

Fig. 1 is a sectional view of an ignition timer and distributor unit embodying the 35 present invention.

Fig. 2 is a plan view of the timer with the distributor head removed.

Fig. 3 is a sectional view on the line 3—3 of Fig. 1.

40 Figs. 4 and 5 are sectional views on the lines 4—4 and 5—5 of Fig. 2.

The ignition timer comprises a cup or housing 20 having a shank 21 which provides a bearing for a shaft 22. The shaft 22 is provided with a groove 23 into which a washer 24 is swaged so that the washer will provide a collar which rests upon the finished surface 25 of the housing in order to support the shaft 22 vertically. The shaft 22 is provided 50 with a knurled portion 22^a over which a

weight supporting plate is forced in order to provide a driving connection between the shaft 22 and the plate 26. Plate 26 carries pivot studs 27 each pivotally supporting a flat weight 28 which slides across a ridge 29 55 provided by the weight supporting plate 26. Each weight 28 carries a stud 30 received by slot 31 in the weight supporting plate 26 in order to limit rotation of the weight in either direction. Each weight 28 is provided with 60 a lever arm 32 for engaging a lever arm 33 which is provided by a plate 34 which, together with a washer 35 and a weight retaining plate 36, is secured upon the reduced, knurled end 37 of a cam sleeve 38. These 65 parts are held in assembled relation by staking the end of the sleeve 38 as indicated at 40.

The weight retaining plate 36 is provided with extensions 41 overlying the weights 28 and normally spaced therefrom by an amount 70 corresponding to the thickness of the washer 35. The weight retaining plate 41 is provided with a notch 42 which cooperates with one of the spring studs 43 with which the lever arm 33 is provided. In this way the 75 weight retaining plate 41 is maintained in a definite relation to the weights 28.

The weights 28 are normally held in innermost position by springs 44 attached at their ends to the pivot studs 27 and the spring studs 80 43 respectively. As the rotation of the shaft increases the weights 28 will rotate about their pivots 27 and will move outwardly toward the cylindrical wall of the cup 20 against the action of the springs 44 and will rotate 85 the sleeve 38 in such direction as to advance the timing of the ignition.

The cam sleeve 38 is provided with cam lobes 50 for engaging a rubbing block 51 attached by rivet 52 to a circuit breaker lever 90 53 supported by non-conducting hub 54 upon a pivot stud 55 riveted to a circuit breaker plate 56 having ears 57 for receiving screws 58 by which the plate 56 is supported by the timer housing 20. The lever 53 carries a contact 60 engageable with a relatively stationary contact 61 carried by contact bracket 62 which is pivoted around a shoulder portion 63 of the stud 55. The contacts are held yielding in engagement by a leaf spring con- 100

ductor 64 attached at one end to a terminal screw 65 insulatingly attached to the housing 20, and attached at the other end by the rivet 52 to the lever 53.

5 The contact bracket 62 is adjustable about the pivot stud 55 for the purpose of varying the amount of contact separation. This adjustment is effected by turning a screw driver slotted disc 66 received by a slot 67 in the bracket 62 and having a shank 68 eccentric to the disc 66 and pivotally attached to the plate 56. The bracket 62 is clamped to the plate 56 in the desired position of adjustment by a screw 69 passing through an arcuate slot 70 and having threaded engagement with the plate 56.

10 That portion of the shaft 42 which provides a bearing for the cam sleeve 48 is lubricated by oil fed by capillary attraction from 20 a fibrous plug 75 saturated with lubricating oil.

15 The cam sleeve 38 drives a distributor rotor 80 carrying a segment 81 which rotates past a plurality of distributor posts 82 supported in a circular row in a non-conducting distributor head 83. The segment 81 is attached to a leaf spring 84 carrying a button 85 biased into engagement with a button 86 carried by a conducting socket member 87 25 supported centrally by the head 83. Each post 82 is integral with a conducting socket 88.

20 It is apparent from the foregoing description that the present invention provides for 35 the retention of the weights upon the weight supporting plate in an exceedingly simple manner. The member for retaining both of the weights is provided by single punching of sheet material and this punching is held 40 by a plain washer in correct spaced relation to the weights. The cost of producing the ignition timer has been increased only by the cost of producing these parts. The cost of assembling them is practically negligible 45 since the operation of staking the lever plate 34 to the cam sleeve 38 at the same time causes the washer and plate 36 to be assembled.

50 While the form of embodiment of the present invention as herein disclosed, constitutes a preferred form, it is to be understood that other forms might be adopted, all coming within the scope of the claims which follow.

55 What is claimed is as follows:

1. An ignition timer comprising, in combination, a drive shaft, a weight plate supported thereon, flat weights pivotally supported by the plate eccentric to its axis, a cam sleeve rotatable coaxially of the shaft, a flat plate attached to the cam sleeve and having 60 lever arms cooperating with the pivoted weights so that the sleeve will rotate as the weights move about their pivots, a flat plate attached to the cam sleeve and extending over the weights but spaced therefrom to permit the weights to pivot freely, and springs 65

for restraining outward movement of the weights.

2. An ignition timer comprising, in combination, a drive shaft, a weight plate supported thereon, flat weights pivotally supported by the plate eccentric to its axis, a cam sleeve rotatable on said shaft and having a reduced end portion, a flat plate pressed fitted to said end portion and having lever arms engaged by the weights, a relatively thin flat plate located on the sleeve and between the lever arm plate and the shoulder of the reduced end portion of the sleeve, said thin plate having parts extending over the weights to limit their separation from the weight supporting plate and springs for restraining outward movement of the weights. 70

3. An ignition timer according to claim 2 in which each spring is connected with the weight plate and with a spring stud on one of said lever arms of the plate attached to the cam sleeve, and in which one of the spring studs prevents turning the thin flat plate relative to the cam sleeve. 85

4. An ignition timer comprising in combination, a drive shaft, a weight plate drivingly fixed to said shaft, weight levers pivoted to said plate eccentric of the shaft, a cam sleeve rotatably supported upon said shaft, said sleeve being provided with a flat plate attached to one end thereof and having lever arms cooperating with the pivoted weights so that the sleeve will rotate as the weights move about their pivots, and additional means attached to the cam sleeve and extending over the weights, but spaced therefrom, to permit the weights to pivot freely, and to limit separation of the weights from their supporting plate, and means for restraining outward movement of the weights. 90

5. An ignition timer comprising in combination, a drive shaft, a weight plate drivingly fixed to said shaft, weight levers pivoted to said plate eccentric of the shaft, a cam sleeve rotatably supported upon said shaft, said sleeve having means thereon to associate the movement of the weights about their pivots with a definite rotation of the sleeve upon the shaft, additional means attached to the cam sleeve and extending over the weights, but spaced therefrom, to permit the weights to pivot freely, and to limit separation of the weights from their supporting plate, and means for restraining outward movement of the weights. 100

110 In testimony whereof I hereto affix my signature.

JOHN T. FITZSIMMONS.
